UNITED STATES PATENT OFFICE.

GEORGE E. CRUMP, OF NEW YORK, N. Y.

DESIGN FOR AN AUXILIARY CHANGE-COUNTER.

SPECIFICATION forming part of Design No. 27,863, dated November 16, 1897.

Application filed May 29, 1897. Serial No. 638,812. Term of patent 7 years.

To all whom it may concern:

Be it known that I, GEORGE E. CRUMP, a citizen of the United States, residing at New York, in the county and State of New York, 5 have invented and produced a new and original Design for an Auxiliary Change-Counter, of which the following is a specification, reference being had to the accompanying drawing, forming part thereof, and in which is 10 presented a perspective view of an auxiliary change-counter bearing and incorporating my design.

The leading feature of the design consists in the form and configuration of the auxiliary change-counter, as shown in the accompanying drawing.

In the drawing, A designates the auxiliary

change-counter as a whole, B the part thereof to face the cashier or person delivering the change, and C the part thereof to face the 20 person receiving the change. The part B has the downwardly-inclined face D and vertical edge E, and the part C is a flat shelf or flange at the base of the said edge E, as shown.

What I claim is—

The design for an auxiliary change-counter, substantially as shown and described.

In testimony whereof I affix my signature in presence of two witnesses.

GEORGE E. CRUMP.

Witnesses:

CHAS. C. GILL,
E. JAS. BELKNAP.
